SECTIONAL SOFA

Hubert Howard Watson and Mike Stewart Watson, Galax,
Va., assignors to Sawyers Furniture Company, Galax,
Va., a corporation of Virginia

Filed July 31, 1969, Ser. No. 18,491

Term of patent 14 years

Int. Cl. D6—01

U.S. Cl. D15—11

FIG. 1 is a perspective view of a sectional sofa showing our new design;

FIG. 2 is an end elevational view of that section of the sectional sofa shown at the left portion of FIG. 1 and viewed from an end of said section; and

FIG. 3 is an enlarged fragmentary view showing the lower right front corner of the sofa of FIG. 1 in greater detail.

The end of the sofa not shown in the right in FIG. 1 is a mirror image of the end shown in FIG. 2 while the back of the sofa is conventional.

We claim:

The ornamental design for a sectional sofa, as shown and described.
